SHAPING APPARATUS FOR TUBELIKE ARTICLES

John F. P. Farrar, Maywood, Ill., assignor to Chicago Metal Hose Corporation, Maywood, Ill., a corporation of Illinois

Application January 6, 1943, Serial No. 471,439

13 Claims. (Cl. 153—73)

1

This invention relates to shaping apparatus, particularly for the shaping of tube-like articles by the internal working thereof. Such tube-like articles may be relatively short such as bands, ferrules and the like, or longer in the form of elongated metal tubings.

It is an object of the invention to provide improved apparatus for shaping or profiling tube-like articles such, for example, as metal ferrules or tubings by the internal working thereof to effect an outward radial projection of the article body into the desired shape or profile. In accordance with the principles of the invention, the working tool may be arranged within the tube-like article to be shaped or worked, and so controlled as to progressively project the body of the article radially outwardly into the desired shape or profile.

A further object of the invention is to provide apparatus of the type stated wherein the material of the article being shaped is subjected to minimum internal strain during the shaping process.

A still further object of the invention is to provide apparatus of the type stated which are satisfactorily operable upon tube-like articles of extended length, such as elongated metal tubings or the like.

Another object of the invention is to provide improved apparatus for corrugating metal tubing.

Still another object of the invention is to provide a metal tubing having improved durability and other operating characteristics.

Various other objects, advantages and features of the invention will be apparent from the following specification when taken in connection with the accompanying drawings, wherein a preferred embodiment of the invention is set forth for purposes of illustration.

In the drawings, wherein like reference numerals refer to like parts throughout:

Fig. 1 is a general assembly view, diagrammatic in form, of a tube forming apparatus constructed in accordance with and adapted to carry out the principles of the invention;

Fig. 2 is a sectional view through the apparatus of Fig. 1, on the line 2—2 thereof, and more particularly showing the mechanism for holding the tubing during the shaping operation;

Figs. 3 and 4 are detail views of the tube feeding mechanism, Fig. 4 being taken on the line 4—4 of Fig. 3;

Fig. 5 is a partial detail view of the tube supporting mechanism, on the line 5—5 of Fig. 1;

Fig. 6 is a detail sectional view of the working

2

or shaping head, adapted to be disposed internally of the tube or band being shaped;

Fig. 7 is a view similar to Fig. 8, but showing the parts in a different position of operation;

Fig. 8 is a horizontal sectional view of the structure of Fig. 6, on the line 8—8 thereof;

Fig. 9 is an end view of the working or shaping head, on the line 9—9 of Fig. 6;

Fig. 10 is a view similar to Fig. 9 but showing the parts as adjusted to their Fig. 7 position, and taken as indicated by the line 10—10 of Fig. 7;

Fig. 11 is a sectional transverse view through the working head, on the line 11—11 of Fig. 6, and showing a portion of the tool adjusting or shifting means;

Fig. 12 is a view similar to Fig. 11 but showing the parts in their Fig. 7 position, as indicated by the line 12—12 of Fig. 7;

Fig. 13 is an exploded view showing certain parts of the tool adjusting or shifting means; and

Fig. 14 is a transverse sectional view through the working or shaping head, on the line 14—14 of Fig. 6, and showing another portion of the tool adjusting or shifting means.

In the drawings the invention has been illustrated as applied to the manufacture of annularly corrugated metal tubing by the internal working thereof, as the invention in various of its aspects is particularly adapted to an installation of this character. It is to be understood, however, that the principles of the invention are also adapted for the shaping or profiling of articles including tube-like or band-like ferrules of other kinds and form.

The apparatus illustrated comprises an elongated table or platform 10, Fig. 1, suitably supported by means of legs or uprights as indicated at 11 and 12. The table 10 may be of any desired length, depending upon the length of the tubing or work to be processed.

A support bracket comprising a pedestal member 13 and a cooperating cap member 14, Figs. 1 and 2, is arranged adjacent one end of the table, the pedestal being fixed to the table by suitable means such as bolts 15. The support bracket is provided for releasably supporting the end of the work piece in position to be acted upon by the working or shaping head, as will be best understood by reference to Figs. 1 and 6. In Fig. 6 the working head is generally indicated by the numeral 16, and the work piece is indicated as an elongated metal tubing 17, which may for example comprise a piece of longitudinally welded

tubing to be provided with annular corrugations as indicated at 18, Fig. 1.

The support bracket is adapted to releasably engage or grip the exterior surface of the tubing or work piece, and to this end the cap 14 is pivotally connected to the pedestal 13 by means of a pivotal connection 20, Fig. 2, suitable mechanism being provided for causing the cap and pedestal to grip the tubing when desired. More specifically, a bell-crank lever 21 is pivotally mounted upon the pedestal 13 as indicated at 22, Fig. 2, the upper end of the bell-crank lever being provided with a roller 23 adapted to engage a cam-like projection 24 formed on the end of the cap member 14. The lower end of the bell-crank 15 is connected to an elongated rod 25 which projects downwardly through an opening in the table 10 and is connected at its lower end to a foot lever 26 pivotally mounted as indicated at 27 upon a fixed floor bracket 28. The lever 26 may be provided with a pedal or portion 29 by means of which the lever may be depressed by the operator's foot into the full line position indicated in Fig. 2, a tension spring 30 secured to the lever and to the bracket 28 being provided for normally urging the lever upwardly into its dotted line position. When the lever 26 is in its normal or dotted position, the bell-crank 21 is pivoted clockwise from the position shown in Fig. 2, releasing the roller 23 from the cam projection 24, thereby releasing the cap member 14 from gripping engagement with the tubing and thus permitting axial shifting of the tubing longitudinally of the table 10 by means presently to be described. Additionally, when the roller 23 is released from the cam projection 24, the cap member 14 may be pivoted to an inoperative position as indicated in dotted lines in Fig. 2 to facilitate tube loading operations. Assuming that the cap member is in engagement with the tubing, it will be seen that depression of the foot lever 26 causes engagement of the roller 23 with the cam projection 24 thereby tightly gripping the tubing between the pedestal and cap members.

The means for shifting the tubing axially to bring the desired portion thereof into position to be acted upon by the working or shaping head is best shown in Figs. 1, 3 and 4. This means comprises a bracket 33 adapted to pivotally support a pair of rollers 34 and 35 of rubber or similar material. The roller 34 is pivotally mounted upon a support bolt 36 carried by the bracket and has a ratchet 37 fixed thereto adapted for cooperation with a spring pressed pawl 38 carried upon an operating lever or handle 39 also pivotally mounted upon the bolt 36. An apron or cam member 40 is non-rotatably fixed to the bolt 36, which cam member is adapted to engage the pawl 38 to limit its stroke of engagement with the ratchet wheel. It will be seen that as the handle 39 is manually reciprocated, at each operation thereof the ratchet 37 and its associated feed roller 34 will be rotated a predetermined distance determined by the apron 40, to thereby feed the tubing 17 to the left a predetermined distance. The feeding distance may be varied by substituting appropriate apron members 40, or other means may be provided for predetermining the effective stroke of operation of the pawl.

The cooperating roller 35 which maintains frictional engagement between the tubing and the feed roll 34 is carried by a pair of arms 42 formed on a sleeve 43 pinned to one end of a shaft 44 journaled in the bracket 33. The other end of shaft 44 has pinned thereto an operating lever

or handle 45 by means of which the shaft and the associated arms 42 and 43 may be shifted clockwise as seen in Fig. 3 from an inoperative position to an operative position as shown. When the arms and the roller 35 are shifted to their operative position, they move slightly past vertical dead center into engagement with a stop pin 46 so as to be automatically maintained in such position. When the roller 35 is shifted to its inoperative position the tube 17 may be freely shifted independent of the feeding roller 34 as, for example, during loading or unloading operations. Rollers 34 and 35 may be shaped to conform to the particular size of tubing being processed.

In instances wherein the work piece such as the tubing 17 is of extended length it is desirable to support it at suitable intervals along its length. Such support means is indicated in Figs. 1 and 5, and may conveniently comprise a support bracket 50 slidably mounted within an opening in the table 10. The bracket 50 is bifurcated at its upper end and carries a pair of support rolls 51 and 52 adapted to engage and support the tubing. An adjustment screw 53 is provided for properly adjusting the height of the bracket 50. To this end the adjustment screw is threadedly connected to a frame bracket 54 fixed to the table 10, the end of the screw extending into an opening 55 provided in the lower portion of the bracket 50. It will be seen that as the adjustment screw 53 is turned within the frame bracket 54, the support bracket 50 is correspondingly lowered or raised to bring the support rolls 51 and 52 into proper engagement with the tubing surface. It will be understood that an appropriate number of such support devices are preferably provided along the length of the table 10, in accordance with the length of the work piece being processed.

The working or shaping head 16, and its associated control and operating parts are illustrated in Figs. 1 and 6 to 14 inclusive. Referring to Fig. 6, the working head comprises a shaping or spinning ring 60 suitably profiled on its exterior surface in accordance with the shaping to be imparted to the work piece. The ring or tool 60 is secured by suitable means, such as screws 61 to the outer race 62 of a ball bearing structure, the inner race 63 of the ball bearing being secured to a projection 64 provided on the end of an adjustable cage member 65, the shape of which will be best understood by reference to Fig. 13. The bearing race 63 may conveniently be retained on the end of the projection 64 by means of a securing plate 66 and screw 67 threaded into the end of the projection.

The cage 65 is mounted on the front of a flange 70 formed on the end of the main operating shaft 71 which is adapted to extend along the length of the tube or work piece 17 and to be rotatably driven to effect the operation of the shaping tool, as will be later described. The cage is mounted for rotation with the flange 70 and also for adjustable movement transversely thereof whereby to predetermine the orbit of travel of the projection 64. More specifically, as best shown in Figs. 11 and 13, a pair of guide pieces 72 and 73 are bolted to the front face of the flange 70 by means of bolts or screws 74. These guide pieces, together with the front surface of the flange 70 form a track structure extending transversely of the flange along which the cage 65 is transversely adjustable. To effect the adjustment of the cage, the cage is provided with a central recess 75, as best shown in Fig. 13 within which a cam 76 is operable. This cam is secured to the front end

of a jack shaft 77 rotatably mounted within a counterbore or recess 78, Fig. 6, formed in the end of the main operating shaft 71. To effect the securing of the cam 76 to the end of the jack shaft, the jack shaft is provided with a squared projection 79 on its forward end, as shown in Fig. 11, onto which the cam 76 is press-fitted. It will be seen that as the jack shaft 77 is rotated relative to the main operating shaft 71, the cam 76 is rotated, for example from the position shown in Fig. 11 to the position shown in Fig. 12, whereby to effect the transverse shifting of the cage 65 with its projection 64 transversely of the flange 70 and the axis of the work piece.

To effect the rotation of the jack shaft 77 relative to the main operating shaft, the jack shaft is provided with a pair of helical grooves or slots 81 and 82 cut into the cylindrical surface thereof as indicated in Fig. 6. A pair of pins 83 and 84 are provided, the reduced end portions of which extend, respectively, into these slots. The pins are press-fitted into a sleeve 85 loosely mounted on the shaft 71 for axial movement in respect thereto. Sleeve 85 is provided with an end flange portion 86 fixed to the main body of the sleeve by means of suitable securing means such as screws 87, Fig. 6. The sleeve and end flange, when in assembled position, are shaped to define a groove extending circumferentially of the sleeve within which a ring member 88 is arranged, the sleeve being freely rotatable relative to the ring, as indicated by the ball bearing connections 89.

A ring-like spider 90, Fig. 6, loosely embraces the shaft 71. This spider is provided with a pair of forwardly projecting arms 91 and 92, the ends of which carry pins 93 screw threaded into the ring 88. Also connected to the spider are a pair of arms 94 and 95, Figs. 6 and 8, extending longitudinally of the shaft 71 within the work piece, and adapted to be shifted axially of the shaft and the work piece by means later to be described. The sleeve-like end of the operating shaft 71 is provided with a pair of longitudinal slots 96 and 97, Fig. 6, respectively receiving the pins 83 and 84. The arrangement is also indicated in Fig. 14. It will be seen that as the arms 94 and 95 are shifted axially of the work, for example from the position shown in Fig. 6 to that shown in Fig. 7, the ring 88 and sleeve 85 are correspondingly axially shifted causing the pins 83 and 84 to shift axially in the slots 96 and 97 and thereby through their engagement with the slots 81 and 82, effect the relative rotation of the jack shaft 77 with respect to the main operating shaft 71. It will be understood that all of the parts are rotatable with the operating shaft 71, with the exception of the ring 88 and the spider 90 with its associated parts such as the arms 91, 92 and the arms 94, 95. To this end the ball bearing connection 89 is provided so that while the ring 88 and sleeve 85 are constrained for axial movement together, the sleeve 85 may rotate with the shaft 71, relative to the ring 88.

In order to rotatably support the end of the operating shaft 71 in proper position at its central axis of rotation, the sleeve-like end portion 100 thereof, Fig. 6, is adapted to receive an inner race member 101 of a ball bearing structure held in position by means of a threaded collar 102. The outer race member 103 of this bearing has a collar 104 detachably fixed thereto by suitable means, such as screws as indicated at 105. This collar, which is selected in accordance with the size of the work piece, is just sufficiently smaller than the work piece so as to permit the work

to be axially shifted with respect thereto during loading operations, and also as the work piece is axially shifted to bring new sections thereof into position to be worked upon by the working or shaping tool 60. When the cap member 14 is urged into clamping engagement with the work piece, as previously described, the cap member and the pedestal 13, in cooperation with the collar 104, and the interposed wall of the work piece, provide a support arrangement for supporting the end of the operating shaft 71 during operation of the tool. If desired, the cap and pedestal may be ovaled very slightly to facilitate the gripping of the tube wall against the collar 104. The ball bearing connection permits the collar 104 to remain stationary with the work during rotation of the shaft 71.

To effect the axial shifting of the arms 94 and 95 a lever 110, Fig. 1, is pivotally mounted adjacent the end of the machine table 10, as indicated at 111, the upper end 112 of the lever being formed into a yoke for connection with the arms 94 and 95. The lower end of the lever is connected by means of a rod 113 to a pivoted handle or operating lever 114 pivoted to the table 10 as indicated at 115 and adapted for manipulation by the machine operator.

To effect the rotation of the main operating shaft 71, the end of the shaft remote from the working tool is adapted to be rotatably received within a bearing structure 118, Fig. 1, fixed to the table 10, the end of the shaft having fixed thereto a pulley such as indicated at 119. This pulley is driven from a belt 120 connected to a driving pulley 121 adapted to be selectively clutched to and unclutched from a constantly operating motor 122 by means of a clutch structure 123. The clutch 123 may be of any conventional design suitable for connecting and disconnecting the pulley 121 from its driving motor. A lever 124 is provided for shifting the clutch, this lever being connected by means of a rod 125 to a manual control handle or lever 126 pivoted to a floor bracket as indicated at 127 and adapted for operation by the machine operator.

In the operation of the mechanism described, and assuming that the main driving motor 122 is rotating, the cap member 14, Fig. 2, and the compression roller 35, Fig. 4, of the feeding mechanism may be moved to inoperative position whereby to permit the ready insertion of a work piece, such as the tubing 17 into the machine. In loading the work, the tubing is slipped onto the working head from the left as seen in Fig. 1, into proper position. The cap 14 is then pivoted into its full line position shown in Fig. 2, and the compression roll 35 of the feeding mechanism brought into engagement with the tubing. Manipulation of the feeding handle 39 will then operate to shift the tubing to the left accurately to bring the desired portion thereof into position to be acted upon by the working or shaping tool. When the tubing has been positioned, the foot lever 26 is operated to clamp it. Thereupon the clutch 123 is closed by means of the lever 126 effecting the rotation of the main operating shaft 71. As the lever 114 is then operated, the arms 94 and 95 are shifted to effect the relative movement of the jack shaft 77 with respect to the main operating shaft, from its Fig. 6 to its Fig. 7 position. During this movement the cam 76 is shifted to effect the transverse adjustment of the cage 65 with its projection 64. Such adjustment causes the rotating projection to move 75 from a position coincident with the axis of the

shaft 71 progressively outwardly as it rotates, thereby assuming a gyratory path of travel. More specifically, the projection 64 moves in a coplanar spiral of progressively increasing size thereby imparting a similar movement to the working or shaping tool 60. The projection 64 rotates with the shaft 71 but the tool 60, while assuming the gyrating motion, is non-rotatable except in so far as rotation may be induced by its contact with the work surfaces. The work, in the particular embodiment shown, is progressively provided with an annular corrugation as indicated at 18a in Fig. 7 and as will be understood by a comparison of Figs. 9 and 10. It will be seen that the cap 14 and pedestal 13 project into close proximity to the shaping tool, thus providing maximum support for the work piece. The cap and pedestal also cooperate to form a support means for the end of the rotating shaft 71, as previously described. After the working head has been retracted to its position as shown in Fig. 6, foot pedal 26 may be operated to release the clamping engagement of the cap 14, and the feed handle 39 thereupon operated to bring a new tubing surface into position to be operated upon by the working head, and the operation repeated.

It will be seen that by the apparatus provided a band-like or tube-like work piece may be internally worked, viz., radially expanded outwardly into a suitable and desired profile. Such operations may be carried out notwithstanding that the work piece is of extended length as indicated in Fig. 1. The invention is thus particularly adapted to the formation of annular corrugations in elongated metal tubing. As perhaps best indicated in Figs. 6 and 9, it will be seen that the working tool 60 is substantially of the same external diameter as the initial internal diameter of the tubing. By this means a maximum contact surface is provided between the work piece and the tool during the forming operation thereby minimizing the strain of the metal fibers. Also, it will be noted that during the forming process the tubing is spun outwardly. Accordingly the reduction in wall thickness of the work piece which takes place during the forming process occurs at the apex of the corrugation as indicated at 18a in Fig. 7. The trough portion of the tubing convolution as indicated at 18b remains of the original tubing wall thickness. By this means a maximum strength is provided in the trough portions of the tubing which trough portions are subjected to the greatest stresses during flexing of the tubing in service. Accordingly, a more durable tube, and a tube of improved operating characteristics is provided.

It is obvious that various changes may be made in the specific embodiment set forth without departing from the spirit of the invention. Accordingly, the invention is not to be limited to the specific embodiment shown and described, but only as indicated in the following claims.

The invention is hereby claimed as follows:

1. Apparatus for working a tube-like work piece comprising means for supporting the work piece, a working tool, means for supporting the tool interiorly of the work piece substantially coaxially thereof, said support means including a member adapted to fixedly grip the wall of the work piece and hold it against rotation, and control means for shifting the work support and tool relative to each other to shift the contact surface of the tool along the work both radially and circumferentially relative to the work piece,

whereby to impart the desired contour to the work piece.

2. Apparatus for working a tube-like work piece comprising means for supporting the work piece, a working tool, means for supporting the tool interiorly of the work piece, said support means including a member adapted to fixedly grip the internal wall of the work piece and hold it against rotation, and control means for shifting the work support and tool relative to each other to shift the contact surface of the tool along the work-piece in a coplanar path of travel extending circumferentially and progressively radially outwardly of the work piece, whereby to impart the desired contour to the work piece.

3. Apparatus for working a tube-like work piece comprising means for supporting the work piece, a working tool, means for supporting the tool interiorly of the work piece, rotatable means for propelling the tool so as to cause the working surface thereof to move circumferentially of the work piece, and means including control mechanism extending longitudinally of the work piece axis for simultaneously shifting the tool transversely of the work piece axis during the operation of said rotatable means, said tool being shiftable from a position substantially coaxial with the axis of the work piece.

4. Apparatus as defined in claim 3, wherein said shifting means comprises a cam normally rotatable with the rotatable means but adjustably shiftable in respect thereto to effect the transverse tool shifting movement.

5. Apparatus for working a tube-like work piece comprising means for supporting the work piece, a ring working tool, said tool being substantially commensurate in size with the diameter of the work piece, means for supporting the tool interiorly of the work piece comprising a stud upon which the ring tool is rotatably mounted, rotatable means for driving the stud so as to cause the working surface of the ring tool to move circumferentially of the work piece, and means including control mechanism extending longitudinally of the work piece axis for simultaneously shifting the stud transversely of the work piece axis during the operation of said rotatable means.

6. An apparatus as defined in claim 5, wherein said stud shifting means comprises a cam normally rotatable with the rotatable means but adjustably shiftable in respect thereto to effect the transverse stud shifting movement.

7. Apparatus for working a tube-like work piece comprising means for supporting the work piece, a ring working tool, means for supporting the tool interiorly of the work piece comprising a stud upon which the ring tool is rotatably mounted, rotatable means for driving the stud so as to cause the working surface of the ring tool to move circumferentially of the work piece, means for simultaneously shifting the stud transversely of the work piece axis during the operation of said rotatable means, and means for controlling the axial shifting of the work piece to bring spaced axial portions thereof into position to be operated upon by the tool, whereby to provide a corrugated tubing structure.

8. Apparatus for working a tube-like work piece comprising means for non-rotatably supporting the work piece, a working tool structure disposed interiorly of the work piece, said working tool structure being adapted to form an annular contour in the work piece and having but a single point of engagement therewith, means for

supporting the working tool structure interiorly of the work piece, said support means including a member adapted to engage the internal wall of the work piece, and control means for shifting the work support and tool relative to each other to shift the contact surface between the tool and the work in a coplanar path of travel extending circumferentially and progressively radially outwardly of the work piece, whereby to impart the desired contour to the work piece.

9. Apparatus for working a tube-like work piece comprising means for supporting the work piece, a working tool structure disposed interiorly of the work piece, said working tool structure being adapted to form an annular contour in the work piece and having but a single point of engagement therewith, means for supporting the working tool structure interiorly of the work piece, and control means including a control lever and a mechanical linkage connecting the control member with the working tool structure for shifting the work support and tool relative to each other to shift the contact surface between the tool and the work in a coplanar path of travel extending circumferentially and progressively radially outwardly of the work piece, whereby to impart the desired contour to the work piece.

10. Apparatus for working a tube-like work piece comprising a pair of cooperable outer and inner clamp members for gripping and non-rotatably holding the work piece, a ring working tool, means for supporting the tool interiorly and substantially coaxially of the work piece comprising a stud upon which the ring tool is rotatably mounted, means rotatable within the work piece

35

and rotatably journaled within the inner of said clamp members for driving the stud so as to cause the working surface of the ring tool to move circumferentially of the work piece, and means for simultaneously shifting the stud transversely of the work piece axis during the operation of said rotatable means.

11. Apparatus as defined in claim 10, wherein said stud shifting means comprises a cam normally rotatable with the rotatable stud driving means, and rotatable at a speed differing from the speed of the rotatable means to effect the transverse stud shifting movement.

12. Apparatus as defined in claim 10, wherein said stud shifting means comprises a member adapted to lie within the work piece and shiftable longitudinally thereof to effect the transverse stud shifting operation.

13. Apparatus for working a tube-like work piece comprising means for non-rotatably supporting the work piece, a working tool structure disposed interiorly of the work piece, said working tool structure being adapted to form an annular contour in the work piece upon engagement therewith, means for moving the working tool circumferentially of the work piece, means including control mechanism extending longitudinally of the work piece axis for shifting the working tool transversely of the work piece axis during its circumferential movement, and means for gauging the axial shifting of the work piece to bring spaced axial portions thereof into position to be operated upon by the working tool, whereby to provide a corrugated tubing structure.

JOHN F. P. FARRAR.
